GRINDING WHEEL FEEDING MECHANISM

John I. Garside, West Boylston, Mass., assignor
to Norton Company, Worcester, Mass., a corpo-
ration of Massachusetts

Application July 28, 1945, Serial No. 607,589

12 Claims. (Cl. 51-2)

1
This invention relates to grinding machines, and more particularly to a fluid pressure operated wheel feeding mechanism.

One object of the invention is to provide a simple and thoroughly practical hydraulically operated wheel feeding mechanism for a grinding machine. Another object of the invention is to provide a semi-automatically controlled wheel feeding mechanism for a grinding machine in which the wheel may be first fed intermittently to round up the work piece, then at a slow continuous body grinding feed, and then allowed to dwell for a predetermined finish grinding or sparking-out period, after which the wheel is automatically returned to an inoperative position.

Another object of the invention is to provide an automatically operated gauge control which serves to stop the grinding feed when the work has been ground to a predetermined size and to set in motion a time delay relay which allows a sparking-out or finish grinding to continue for a predetermined time interval, after which the wheel is automatically and rapidly moved to an inoperative position. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention, is illustrated diagrammatically the improved hydraulically and electrically controlled wheel feeding mechanism, having some portions shown on an enlarged scale to clarify the illustration.

A grinding machine has been illustrated in the drawing comprising a base 10 which supports a longitudinally movable work table 11 on the usual flat way 12 and V-way 13. The table 11 serves as a support for a headstock 14 and a footstock (not shown) rotatably to support a work piece 15 to be ground.

A suitable traversing mechanism may be provided for longitudinally positioning the work table 11 so that the work piece is in the desired position for a grinding operation. This mechanism may comprise a rack bar 16 depending from the under side of the table 11. A gear 17 meshes with the rack bar 16 and is mounted on the end of a shaft 18. The shaft 18 is rotatably journaled in suitable bearings (not shown) which

5 are fixed relative to the base 10. A manually operable traverse wheel 19 is mounted on the outer end of the shaft 18 by means of which the table 11 may be adjusted longitudinally relative to the base 19 as desired.

10 A rotatable grinding wheel 20 is supported at one end of a rotatable wheel spindle 21 which is journaled in suitable bearings (not shown) in a transversely movable wheel slide 22. The slide 22 is slidably supported on the usual flat way and V-way (not shown) formed on the base 10. A driving mechanism is provided for rotating the grinding wheel 20 which may comprise an electric motor 23 which is mounted on the upper surface of the wheel slide 22. The motor 23 is provided with an armature shaft 24 which supports a multi-V-groove pulley 25. The multi-V-groove pulley 25 is connected by multiple V-belts 26 with a multi-V-groove pulley 27 which is mounted on the end of the wheel spindle 21.

15 A suitable feeding mechanism is provided for adjusting the wheel slide 22 transversely relative to the base 10. This mechanism may comprise a rotatable cross feed screw 30 which meshes with a half nut 31 depending from the under side of the wheel slide 22. The feed screw 30 is slidably keyed at its left-hand end in a hollow sleeve 32 which is formed integral with a rotatable shaft 33. The shaft 33 is journaled in suitable bearings (not shown) which are fixedly mounted relative to the base 10. A manually operable feed wheel 34 is mounted on the front of the machine base and is operatively connected to rotate the shaft 33 and the feed screw 30 manually to adjust the position of the wheel slide 22 and the grinding wheel 20 as desired.

20 It is desirable to provide a suitable power operated mechanism for moving the wheel slide 22 rapidly to and from a grinding position and to aid in automatically controlling the grinding feeding movement thereof. This mechanism preferably comprises a hydraulic cylinder 35 which is supported in fixed relation with the base 10. A slidably mounted piston 36 is mounted within the cylinder 35 and is operatively connected to a double end piston rod 37. The left-hand end of the piston rod 37 is rotatably connected to a slidably mounted non-rotatable sleeve 38 which also rotatably supports the right-hand end of the feed screw 30. When fluid under pressure is admitted through a pipe 39 into a cylinder chamber 40 at the right-hand end of the piston 36, the piston 36 will move toward the left to transmit an axial feeding movement to the feed screw 30 and a forward feeding move-

ment to the grinding wheel slide 22 and the grinding wheel 20. During this movement, fluid within a cylinder chamber 41 formed at the left-hand end of the cylinder 35 exhausts through a pipe 42.

Control valve

A suitable feed control valve 43 is provided for controlling the admission to and exhaust of fluid from the cylinder 35. This valve is preferably a piston type valve comprising a valve stem 44 having formed integrally therewith valve pistons 45, 46, 47 and 48. A compression spring 49 serves normally to hold the valve stem 44 in a right-hand end position as illustrated in the drawing. A push type solenoid 50 is provided which when energized will shift the valve stem 44 toward the left to shift the valve 43 into its reverse position.

Dash pot-feed regulator

A wheel feed regulator 55 is provided for retarding the rapid movement of the wheel slide 22 caused by the piston 36. This regulator 55 is preferably a dash pot type mechanism including a pair of dash pot pistons 56 and 57 which are arranged on diametrically opposite sides of the piston rod 37. Compression springs are provided normally to urge the dash pot pistons 56 and 57 toward the right. A sleeve 58 is adjustably mounted on the right-hand end of the piston rod 37. The sleeve 58 is provided with a flange 59 which may be formed integral with the sleeve 58 or may be formed in two parts, as indicated in the drawing. The flange 59 is arranged so that it will simultaneously engage both of the dash pot pistons 56 and 57 when the piston rod 37 is moved toward the left. An adjustable stop screw 60 is provided to limit the rearward movement of the flange 59 toward the right and thus determine the inoperative position of the dash pot pistons 56 and 57. An adjustable collar 61 is threaded onto a threaded portion 62 of the piston rod 37. This collar 61 is adjusted so that when the piston 36 has moved to a predetermined position in its stroke so that the grinding wheel 20 is about to engage the work piece to be ground, the collar 61 will engage the sleeve 58 and thereby start movement of the dash pot pistons 56 and 57 toward the left. Fluid within the dash pot chambers is thereby compressed and forced out through a passage 63, a needle valve 64, and a pipe 65 into a reservoir 66. By adjusting the needle valve 64, the speed of the feeding movement imparted to the grinding wheel 20 may be varied as desired.

In certain grinding operations, it may be desirable to cut off the exhaust of fluid through the pipe 65 thereby to stop the forward feeding movement, as controlled by the needle valve 64, automatically in timed relation with the movement of other parts of the grinding wheel feeding mechanism to be hereinafter described. To accomplish this result, a piston type valve 67 is provided in the pipe line 65 between the needle valve 64 and the reservoir 66. The valve 67 is a normally open valve and is normally held in the position illustrated in the drawings by means of a compression spring. An electric pull-type solenoid 68 is provided automatically to close the valve 67 when the solenoid 68 is energized in a manner to be hereinafter described.

Fluid system

A fluid pressure system is provided for supplying the desired fluid under pressure for the operating mechanisms of the machine comprising a

motor driven fluid pressure pump 70 which draws fluid through a pipe 71 from a reservoir 72 and passes fluid under pressure through a pipe 73 to the feed control valve 43. An adjustable pressure relief valve 74 is provided in the pipe line 73 which serves to exhaust excess fluid under pressure directly into the reservoir 72 so as to maintain the desired operating pressure within the hydraulic system.

Fluid under pressure passing through the pipe 73 enters a valve chamber 75 located between the valve pistons 46 and 47 of the feed control valve 43. In the position of the valve 43 as illustrated, fluid under pressure entering the valve chamber 75 passes out through the pipe 42 into the cylinder chamber 41 to move the piston 36 toward the right into an inoperative position. During this movement, fluid within the cylinder chamber 40 exhausts through the pipe 39, through a valve chamber 76 located between the valve pistons 45 and 46, and passes out through an exhaust pipe 77 which conveys exhaust fluid back to the reservoir 72. A throttle valve 78 is provided in the pipe line 77 by means of which the rate of exhaust of fluid from the feed control valve 43 may be readily controlled to regulate the speed of movement of the grinding wheel and its supporting slide 22 to a rearward position.

Displacement Cylinder

In a plunge-cut grinding operation it is desirable to provide an intermittent rather than a continuous infeeding movement of the grinding wheel so that the grinding wheel 20 may be advanced by a predetermined amount and the grinding wheel allowed to grind the work piece 15 being ground before the wheel 20 is again advanced. It has been found that by such a feeding mechanism, the work may be more readily rounded-up to a precise cylindrical form and size. In order to provide a relatively slow infeeding movement of the grinding wheel which may be operated either continuously or intermittently, it is desirable to provide a suitable control mechanism whereby fluid exhausting from the dash pot cylinders may be readily controlled as desired. In the preferred construction, a displacement cylinder 80 is provided having a longitudinally movable displacement plunger 81 contained therein. The plunger 81 is preferably actuated hydraulically by means of a piston 82 which is slidably mounted in a cylinder 83. A pipe 84 connects the dash pot cylinder chambers with the displacement cylinder 80 so that as the displacement plunger 81 is moved toward the left, the capacity of the displacement cylinder 80 will be increased, thereby allowing a predetermined amount of fluid to pass from the dash pot cylinder chambers into the displacement cylinder 80, thus allowing the grinding wheel 20 to move forward under the pressure applied to the piston 36. By controlling the rate of movement of the displacement rod 81, the rate of feeding movement of the grinding wheel 20 may be readily varied as desired. If the displacement rod 81 is moved at a slow continuous rate toward the left, a slow precise continuous infeed of the grinding wheel 20 may be obtained. If the rod 81 is moved intermittently toward the left at slow intervals, a slow intermittent precise feeding movement of the grinding wheel 20 may be obtained.

The cylinder 83 is preferably connected so that the piston 82 will be actuated in timed relation with the actuation of the feed control valve 43. A

pipe 85 connects the valve chamber 76 with a chamber 86 formed at the right-hand end of the cylinder 83. In the position of the valve 43 shown in the drawing, fluid within the cylinder chamber 86 may exhaust through the pipe 85, through the valve chamber 76, and through the pipe 77 into the reservoir 72.

A pipe 87 is connected between the valve 43 and a check valve 88. The check valve 88 is connected by a pipe 89 with a cylinder chamber 90 formed at the left-hand end of the cylinder 83. In the position of the control valve 43 illustrated in the drawings, fluid under pressure in the valve chamber 75 may pass through the pipe 87, through the check valve 88 and the pipe 89 into the cylinder chamber 90 to move the piston 82 into the position illustrated in the drawing.

During the forward movement of the grinding wheel 20, it is desirable to control the rate of exhaust of fluid from the cylinder chamber 90 so as to provide the desired continuous rate of infeeding movement when desired. A pipe 91 is connected between the pipe 89 and a piston type valve 92 which is normally held in an open position by means of a compression spring. A pull type solenoid 93 is provided automatically to close the valve 92 when desired in timed relationship with other mechanisms of the machine when it is desired to cut off the exhaust of fluid through the pipe 91. An adjustable throttle valve 94 is provided in a pipe line 95 which connects the throttle valve 94 with the pipe 87. When fluid exhausts through the valve 92 and the throttle valve 94, it passes through the pipe 95 and the pipe 87 into a valve chamber 96 formed between the valve pistons 47 and 48 when the valve stem 44 is in its left-hand end position and passes out through the exhaust pipe 77 into the reservoir 72.

Metering valve

It is desirable during portions of the grinding operation to provide an intermittent fine precise feeding movement of the grinding wheel 20. This is preferably accomplished by means of a metering valve 100 which comprises a hollow slidably-mounted piston-type valve member 101. A shuttle type valve 102 is slidably mounted within the valve member 101. The valve member 101 is preferably actuated automatically by means of a piston rod 103 and a pair of adjustably mounted collars 104 and 105 in a manner to be hereinafter described. An adjustable stop screw 106 is provided which is screw threaded into an end cap 107 which encloses the left-hand end of the valve member 101. The screw 106 serves to limit the movement of the shuttle valve 102 and thereby to regulate the amount of exhaust metered from the cylinder chamber 90 of the cylinder 83. A pipe 108 connects the pipe 89 with ports 109 and 110 in the valve 100. A pair of exhaust ports 111 and 112 are connected by pipes 113 and 114 respectively with the exhaust pipe 77.

When an intermittent feed of the grinding wheel 20 is desired, the valve 92 is closed automatically in a manner to be hereinafter described so that fluid under pressure exhausting from the cylinder chamber 90 exhausts through the pipe 89, through the pipe 108, into the ports 109 and 110. The valve stem 103 is shown in its extreme right-hand end position. When the valve stem 103 is moved toward the left automatically in a manner to be hereinafter described, the valve member 101 will move toward the left until a

port 115 coincides with the port 110 so that fluid may exhaust from the cylinder chamber 90 into a valve chamber 116 to move the shuttle valve 102 toward the left into engagement with the stop screw 106. This movement allows a predetermined quantity of fluid to exhaust from the chamber 90, thereby allowing a predetermined movement of the displacement rod 81 which allows a predetermined forward feed of the grinding wheel 20.

The valve 100 is illustrated on an enlarged scale to clarify the construction as compared with the cylinder 83 and associated parts. During the exhaust of fluid into the valve chamber 116, a portion of the fluid within a chamber 117 exhausts through a port 118 and the port 111, through the pipe 113 and the exhaust pipe 77, into the reservoir 72. It should be noted that only enough fluid is exhausted from the chamber 117 to take care of the displacement caused by the movement of the shuttle valve 102 toward the left. A similar operation is provided when the valve stem 103 again moves toward the right into the position illustrated in the drawings. A predetermined quantity of fluid will be metered from the cylinder chamber 90 into the valve chamber 117 to move the shuttle valve 102 toward the right, thus allowing a predetermined infeed of the grinding wheel 20 by a predetermined movement of the displacement rod 81.

Fluid motor

In order to provide an automatic intermittent plunge-cut feed, it is desirable intermittently to reciprocate the valve stem 103. A hydraulically operated fluid pressure motor 119 is provided for actuating the valve stem 103. The fluid motor 119 is identical with that shown in the prior U. S. patent to Wallace H. Wood, No. 2,212,871, dated August 27, 1940, to which reference may be had for details of disclosure not contained herein. The motor 119 comprises a cylinder 120 which contains a slidably mounted piston 121. The piston 121 is connected to the right-hand end of a piston rod 122. A yoked member 123 is provided on the left-hand end of the piston rod 122 which straddles the valve stem 103 and is arranged in the path of the collars 104 and 105. A suitable control valve is provided automatically to reciprocate the piston 121 continuously, comprising a valve stem 124 which is fixedly mounted relative to a hollow slidably-mounted piston-type pilot valve 125. A shuttle type reversing valve 126 is slidably mounted within the hollow pilot valve 125. The valve stem 124 of the pilot valve 125 is provided with a pair of adjustably mounted collars 127 and 128 which are arranged to engage an upwardly extending portion 129 of the yoked member 123. The collars 127 and 128 are actuated by movement of the piston 121 to determine the length of the stroke of the piston 121. This motor 119 is arranged automatically to transmit a reciprocatory motion to the yoked member 123 which in turn serves to actuate the metering valve 100 in a manner hereinabove described.

A normally closed valve 130 is provided to control the admission of fluid under pressure to the motor 119. The control valve 130 is normally held in a downward or closed position by means of a compression spring. An electric solenoid 131 is provided which when energized will raise the valve to admit fluid under pressure from the pipe 73 into a pipe 132 which admits fluid under pressure to the pilot valve 125 so as to start and continuously reciprocate the piston 121. Fluid exhaust

from the motor 119, through a pipe 133, and through an adjustable throttle valve 134, into the exhaust pipe 11, and returns to the reservoir 72. By adjustment of the throttle valve 134, the speed of reciprocatory movement of the piston 121 may be readily controlled so as thereby to control the rate of actuation of the metering valve 100 and thus provide either a slow intermittent or a rapid intermittent feeding movement of the grinding wheel as desired.

To facilitate filling the dash pot cylinders and the reservoir 66, a valve 140 is connected in the pipe line 73 which when open may pass fluid through a pipe 141 and a ball check valve 142 into the dash pot cylinders and also through a pipe 144 into the reservoir 66. The valve 140 is utilized only when it is necessary to replenish fluid in the dash pot system.

Gauge head

In order precisely to control the work size, a gauging mechanism is preferably provided such as that, for example, shown in the patent to Shubel A. Foster, No. 2,267,559, dated December 23, 1941, to which reference may be had for details of disclosure not contained herein. As shown in the drawing, this gauging device comprises a caliper 145 which is pivotally supported on a pivotally mounted bracket 146. One end of the bracket 146 is pivotally mounted on a wheel guard 147 which surrounds the grinding wheel 20. The caliper 145 is arranged to be swung from an inoperative position, as shown in the drawing, in a clockwise direction, then downwardly, and then in a counterclockwise direction into operative engagement with the work piece 15 being ground. When the work piece has been reduced to a predetermined size, electric contacts 148 within the caliper head are made to close a circuit which serves to energize a relay 149 which is operatively connected to energize the solenoid 93 and thereby close the valve 92 and thus stop the continuous infeed or body feed of the grinding wheel 20 into the work 15 and at the same time serves to start a time delay relay 150.

Time relay

The time delay relay 150 is a standard electrical relay such as, for example, the "Microflex" automatic instantaneous reset timer manufactured by the Eagle Signal Corporation of Moline, Illinois. When the time relay 150 timing the period of dwell during which there is no infeed of the grinding wheel 20 has completed a predetermined time interval, the time delay relay 150 serves to break a circuit and thus deenergize the solenoid 50, thereby releasing the compression of the spring 49 which returns the feed control valve 43 into the position illustrated in the drawing, thus admitting fluid under pressure into the cylinder chamber 41 of the cylinder 35 rapidly to move the piston 36 together with the wheel slide 22 and grinding wheel 20 toward the right into an inoperative position.

A manually operable control lever 155 is provided for starting a grinding cycle or, if necessary, stopping the grinding cycle during a grinding operation in case of emergency. The control lever 155 is pivotally mounted on a stud 156 and is arranged so that when rocked in a counterclockwise direction, it will close a push button switch 157 to start a grinding cycle. If it is desired to stop the grinding operation during a grinding cycle, the control lever 155 may be rocked in a clockwise direction to close a push

button switch 158 which interrupts the grinding cycle and immediately and automatically returns the grinding wheel and its supporting slide to an inoperative position.

Operation

The operation of this improved feeding mechanism will be readily apparent from the foregoing disclosure. Assuming all of the adjustments have previously been made and a work piece 15 has been loaded in an operating position ready for a grinding operation, the operator rocks the control lever 155 in a counterclockwise direction to close the push button start switch 157. This movement energizes a relay 160 which in turn serves to energize the solenoid 50 to shift the valve stem 44 of the feed control valve 43 toward the left to admit fluid under pressure into the cylinder chamber 40 rapidly to move the piston 36, the wheel slide 22, and the grinding wheel 20 toward the left so that it approaches the work piece 15. Before the grinding wheel 20 engages the work piece 15, the flange 59 engages the dash pot pistons 56 and 57 so that continued forward advance of the wheel is slowed down to a cushioning or shoulder feed in the case of a shoulder grinding operation, the speed of which is governed by the setting of the needle valve 64. The grinding wheel continues to advance at the cushioning feed or shoulder grinding feed until the screw 51 engages and closes the limit switch 52. The closing of the limit switch 52 serves to energize a relay 161 and a relay 162. Energizing of the relay 161 serves to energize the solenoid 68 to close the valve 67, thus stopping the cushioning or shoulder grinding feed. Energizing of the relay 162 serves to energize the solenoid 93 to close the valve 92, thereby preventing passage of oil therethrough so as to prevent a body grinding feed being obtained. Energizing of the relay 162 also energizes the solenoid 131 to open the valve 130 which allows passage of fluid under pressure through the pipe 132 to start the continuous reciprocation of the piston 121 which in turn serves intermittently to actuate the metering valve 100. The metering valve 100 allows an intermittent exhaust of a predetermined amount of fluid from the cylinder chamber 90 of the cylinder 83 which in turn withdraws the displacement plunger 81 a predetermined amount to produce an intermittent advance of the grinding wheel by allowing a periodic predetermined quantity of fluid to exhaust from the dash pot cylinders through the pipe 84 into the displacement cylinder 80.

The gauge head 145 may now be placed in operative position in engagement with the work piece 15. The intermittent feed of the grinding wheel continues until the screw 53 engages and opens the limit switch 54 which opens a circuit to deenergize the relay 162. Deenergizing the relay 162 serves to deenergize the solenoid 131, thus allowing the released compression of a spring to close the valve 130 to stop the intermittent infeed of the grinding wheel. At the same time, deenergizing the relay 162 serves to deenergize the solenoid 93, thus allowing the released compression of a spring to open the valve 92 to start a fine continuous body feed of the wheel toward the work axis by allowing fluid to exhaust from the cylinder chamber 90, through the pipe 91, through the valve 92, and through the throttle valve 94 at a relatively slow rate, thus causing a further continuous movement of

the displacement plunger 81 to grind the work piece by a continuous infeed or body feed.

This continuous infeed or body feed continues until the work has been reduced to a predetermined size at which time the contacts 148 in the gauge 145 close to energize the relay 149. Energizing the relay 149 serves to energize the solenoid 93 to close the valve 92 and thereby shut off the body feed of the grinding wheel 22. At the same time, energizing of the relay 149 sets the time delay relay 150 in motion to control the sparking-out or finish grinding of the work piece 15 while the wheel 20 is held against further forward feeding movement. The finish grinding or sparking-out period continues for a predetermined time interval as governed by the relay 150. After the predetermined time interval has elapsed, the time relay 150 deenergizes the relay 160 which in turn serves to deenergize the solenoid 50, thereby releasing the compression of the spring 49 which in turn moves the valve stem 44 toward the right to position the valve parts in the position shown in the drawing. This shifting movement of the valve 43 serves to pass fluid through the pipe 42 into the cylinder chamber 41 rapidly to move the piston 36, the grinding wheel slide 22, and the grinding wheel 20 toward the right into a rearward or inoperative position, thus terminating the grinding cycle.

When the timer 150 operates to deenergize the relay 160, it also is operatively connected to deenergize the relays 149 and 161 respectively. Deenergizing of the relays 149 and 161 serves to deenergize the solenoid 68 and the solenoid 93 to open the valves 67 and 92 respectively. The gauge is then removed from engagement with the work and the gauge contacts are automatically broken or reset for the next grinding operation and the electric timer 150 automatically resets, ready for the next grinding cycle. The finish ground work piece 15 may then be removed from the machine and replaced by a new work piece to be ground, after which the next grinding cycle may be initiated by actuation of the control lever 155 in a manner hereinabove described.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a grinding machine having a rotatable grinding wheel, a transversely movable slide therefor, means including a piston and cylinder rapidly to move said slide, means including a dash pot feed regulator to slow down the rapid approaching to a relatively slow continuous feeding movement, electrical control means rendered operative after a predetermined slow feed intermittently to produce a fine intermittent feed to round up the surface being ground, means to stop the forward feed for a predetermined time interval, and an electrical time delay relay operatively connected to return said slide and grinding wheel to an inoperative position after a predetermined period of dwell.

2. In a grinding machine having a rotatable grinding wheel, a transversely movable slide

therefor, means including a piston and cylinder rapidly to move said slide, means including a dash pot feed regulator to slow down the rapid approaching to a relatively slow continuous feeding movement for a shoulder grinding operation, electrical control means rendered operative after a predetermined slow feed intermittently to produce a fine intermittent body feed to round up the cylindrical surface being ground, a work sizing gage automatically to stop the forward feed for a predetermined time interval, and an electrical time delay relay operatively connected to return said slide and grinding wheel to an inoperative position after a predetermined period of dwell.

3. In a grinding machine having a rotatable grinding wheel, a transversely movable slide therefor, means including a piston and cylinder rapidly to move said slide, means including a dash pot feed regulator to slow down the rapid approaching to a relatively slow continuous feeding movement, means rendered operative after the wheel reaches a predetermined position intermittently to exhaust fluid from said regulator to produce a fine intermittent feed of the grinding wheel, means to control continuous exhaust fluid from said regulator to produce a fine continuous plunge-cut feed, means automatically to stop said feed for a predetermined time interval, and an electrical time delay relay operatively connected to return said slide and wheel to an inoperative position after said time interval has elapsed.

4. In a grinding machine having a rotatable grinding wheel, a transversely movable slide therefor, means including a piston and cylinder rapidly to move said slide, means including a dash pot feed regulator to slow down the rapid approaching to a relatively slow continuous feeding movement for a shoulder grinding operation, means rendered operative after the wheel reaches a predetermined position intermittently to exhaust fluid from said regulator to produce a fine intermittent feed of the grinding wheel to round up the cylindrical surface being ground, means to control continuous exhaust of fluid from said regulator to produce a fine continuous plunge-cut feed to reduce said surface to a predetermined size, means automatically to stop said feed for a predetermined time interval, and an electrical time delay relay operatively connected to return said slide and wheel to an inoperative position after said time interval has elapsed.

5. In a grinding machine having a rotatable grinding wheel, a transversely movable slide therefor, means including a piston and cylinder rapidly to move said slide, a control valve therefor, means including a dash pot feed regulator to slow down the rapid approaching to a relatively slow shoulder grinding feed, means to intermittently exhaust fluid from said regulator to produce a fine intermittent feed to round up the work, means continuously to exhaust fluid from said regulator to produce a fine continuous feed of the grinding wheel relative to the work, a work sizing gauge automatically to stop said continuous feed when the work has been reduced to a predetermined extent, a time delay relay which is set in motion by said gauging device while maintaining the grinding wheel in grinding engagement with the work for a predetermined finish grinding period, and means actuated by said relay after a predetermined time interval to shift said control valve and thereby terminate the grinding operation.

6. In a grinding machine having a rotatable

grinding wheel, a transversely movable slide therefor, means including a piston and cylinder rapidly to move said slide, a control valve therefor, means including a dash pot feed regulator to slow down the rapid approaching to a relatively slow shoulder grinding feed, means intermittently to exhaust fluid from said regulator to produce a fine intermittent feed to round up the work, means continuously to exhaust fluid from said regulator to produce a fine continuous feed of the grinding wheel relative to the work, means automatically to stop said continuous feed when the work has been reduced to a predetermined extent, a time delay relay which is set in motion when the continuous feed is stopped while maintaining the grinding wheel in grinding engagement with the work for a predetermined finish grinding period, and means actuated by said relay after a predetermined time interval to shift said control valve and thereby terminate the grinding operation.

7. In a grinding machine as claimed in claim 5, the combination with the parts and features therein specified, of a displacement cylinder and rod to control the exhaust of fluid from said dash pot feed regulator, a hydraulic piston and cylinder to actuate said displacement rod so as to increase or decrease the capacity of said displacement cylinder, means intermittently to exhaust a predetermined amount of fluid from said hydraulic cylinder intermittently to move said displacement rod so as to produce a feeding movement of the grinding wheel, and means including a throttle valve continuously to exhaust fluid from said hydraulic cylinder continuously to move said displacement rod so as to produce a fine continuous infeed of the grinding wheel.

8. In a grinding machine as claimed in claim 5, the combination with the parts and features therein specified, of means including a displacement cylinder and rod to control the rate of exhaust of fluid from said dash pot feed regulator, a hydraulic piston and cylinder to actuate said displacement rod so as to increase or decrease the capacity of said displacement cylinder, means including a metering valve to meter the exhaust of fluid from said hydraulic cylinder, a continuously actuated fluid motor to actuate said metering valve to provide an intermittent infeed of the grinding wheel, and a normally open solenoid valve to start and stop said motor.

9. In a grinding machine as claimed in claim 5, the combination with the parts and features therein specified, of means including a displacement cylinder and rod to control the exhaust of fluid from said dash pot feed regulator, a hydraulic piston and cylinder to actuate said displacement rod so as to increase or decrease the capacity of said displacement cylinder, a metering valve to meter the exhaust of fluid from said hydraulic cylinder, means including a continuously actuated fluid motor to actuate said metering valve so as intermittently to move said displacement rod to produce an intermittent feed of the grinding wheel, a solenoid valve to start and stop said motor, means including a solenoid valve to start and stop the continuous exhaust of fluid from said cylinder, and means including a throttle valve to regulate said continuous exhaust of fluid from the hydraulic cylinder to produce the desired continuous infeeding movement of said grinding wheel.

10. In a grinding machine as claimed in claim 5, the combination with the parts and features therein specified, of means including a displace-

ment cylinder and rod to control the exhaust of fluid from said dash pot feed regulator, a hydraulic piston and cylinder to actuate said displacement rod so as to increase or decrease the capacity of said displacement cylinder, a metering valve to meter the exhaust of fluid from said hydraulic cylinder, means including a continuously actuated fluid motor to actuate said metering valve so as intermittently to move said displacement rod to produce an intermittent feed of the grinding wheel, a normally closed solenoid valve to start and stop said motor, means including a normally open solenoid valve to start and stop the continuous exhaust of fluid from said cylinder, and means including a throttle valve to regulate said continuous exhaust of fluid from the hydraulic cylinder to produce the desired continuous infeeding movement of said grinding wheel.

20. 11. In a grinding machine as claimed in claim 5, the combination with the parts and features therein specified, of means including a displacement cylinder and rod to control the exhaust of fluid from said dash pot feed regulator, a hydraulic piston and cylinder to actuate said displacement rod so as to increase or decrease the capacity of said displacement cylinder, a metering valve to meter the exhaust of fluid from said hydraulic cylinder, means including a continuously actuated fluid motor to actuate said metering valve so as intermittently to move said displacement rod to produce an intermittent feed of the grinding wheel, a normally closed solenoid valve to start and stop said motor, means including a throttle valve to regulate the continuous exhaust of fluid from the hydraulic cylinder to produce the desired continuous infeeding movement of said grinding wheel, means including a normally open solenoid valve to start and stop continuous exhaust of fluid from said hydraulic cylinder, and electrical control means simultaneously to actuate said solenoid valves so as to render operative either an intermittent or a continuous feed of the grinding wheel.

45. 12. In a grinding machine having a rotatable grinding wheel, a transversely movable slide therefor, means including a piston and cylinder rapidly to move said slide, a solenoid actuated control valve therefor, means including a dash pot feed regulator having a needle valve to slow down the rapid approaching to a relatively slow shoulder grinding feed, a solenoid valve to cut off fluid exhausting through said needle valve to stop the shoulder grinding feed, a limit switch actuated by movement of said piston, an electric relay operatively connected with said switch and solenoid valve to close the solenoid valve when the limit switch is closed, means including a solenoid valve to start and stop an intermittent feed of the grinding wheel to round up the work, means including a solenoid valve to start and stop a continuous infeed of the wheel to size the work, a second relay which is actuated by the closing of said limit switch to actuate the second and third solenoid valves so as automatically to start an intermittent feed of the grinding wheel when the shoulder grinding feed is terminated to round up the work, a limit switch which is opened after a further continuous feeding movement to actuate the second and third solenoid valves to terminate the intermittent feed and to start a fine continuous feed, a work gauging device including a normally open switch which is closed when the work is ground to a predetermined size, a relay actuated thereby to terminate said continuous feed,

and an electrical time delay relay which is set in motion by closing said gauging device switch to control the duration of a predetermined finish grinding operation, said time relay after a predetermined time interval serving to deenergize said solenoid control valve to cause a rearward movement of the grinding wheel and thus terminate a grinding cycle.

JOHN I. CARSIDE.
